UNITED STATES PATENT OFFICE.

FRANK J. LASKOWSKI, OF BETHLEHEM, PENNSYLVANIA.

GAME.

Application filed November 23, 1925. Serial No. 70,970.

To all whom it may concern:

Be it known that I, FRANK J. LASKOWSKI, a citizen of the United States, residing at Bethlehem, in the county of Northampton and State of Pennsylvania, have invented new and useful Improvements in Games, of which the following is a specification.

This invention relates to game apparatus and embodies amongst other features a ring suspended from a support and adapted to be swung in the direction of a stationary member, with a view of ringing said member to score a point of the game, a register being employed and operated incident to the release of the ring from the member for further play.

Another object of the invention resides in the provision of means for rendering the apparatus inoperative after the ring has been swung in the direction of the stationary member a predetermined number of times, together with means for resetting the register when the ring is again arranged in position for use.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a side elevation of the apparatus showing the normal position of the parts.

Figure 2 is a front elevation.

Figure 3 is a top plan view.

Figure 4 is a sectional view on line 4—4 of Figure 2.

Figure 5 is a view of the register.

Figure 6 is a sectional view on line 6—6 of Figure 5.

The apparatus forming the subject matter of the present invention comprises a box-like base indicated generally at 10, from which rises a supporting structure having an outline or configuration similar to the

letter A. The side members of this supporting structure are indicated at 11 while the cross base or member is indicated at 12. Projecting forwardly from this supporting structure at a point adjacent the upper end thereof is a beam including a fixed section 13 and a relatively movable section 14, the latter being hinged to the section 13 as at 15 and normally disposed in end to end relation therewith. Suspended from the section 14 of this beam and pivotally associated therewith is an arm 16 which supports a cable or the like 17 which carries at its lower end a ring 18, the ring being spaced an appreciable distance from and in advance of a stationary member 19 which projects forwardly from the supporting structure above referred to at an appropriate point. This stationary member 19 is so arranged with relation to the ring 18, that it is possible to encircle the member 19 with the ring when the latter is swung in the direction of said stationary member. It is the object and purpose of the participant to swing the ring 18 in an effort to ring the latter, each participant being allowed so many trials, scoring one each time he successfully throws the ring over the stationary member 19. The arm 16 swings upon its pivot incident to the movement of the ring toward the stationary member, and this fact, coupled with the fact that the ring is suspended by a flexible element, makes it reasonably difficult to ring the member 19 with the ring 18.

Pivotedly supported on the forward end of the stationary member 19 is a hook-like element 20, the lower end of which is connected with the rod 21, the latter being formed with an offset portion 22 pivoted to a lever 23 which in turn is pivoted at a point in its length as at 24 upon the adjacent end of the stationary member 19. The hook-like member 20 is normally arranged substantially at a right angle to the stationary member 19 which adds to the difficulty of successfully throwing the ring over the stationary member, inasmuch as the ring must also pass over the hook-like element 20, which is employed to retain the ring upon the member 19, until the hook-like element 100

is tilted upon its pivot 25 to release the ring. In order to tilt the hook-like element 20 for this purpose it is necessary to swing the lever 23 upon its pivot 24 and thus operate the rod 21, the lever 23 being actuated by a rod 26 arranged longitudinally of the base 10 and provided with a knob or handle 27. However, the rod 21 is normally held against movement, with the hook-like element 20 in the position shown in Figure 1, by means of a pivoted latch 28, one end of which is offset as at 29 to engage the offset portion 22 of the rod 21, thus prohibiting this rod from being moved in a direction to tilt the hook-like element 20. The latch element has its forward extremity 30 obliquely disposed and in close proximity to the hook-like element 20, so that when the ring is successfully thrown over the element 20 and the stationary member 10, the said ring rests upon the adjacent extremity 30 of the pivoted latch 28, thereby rocking this latch element out of engagement from the rod 21. When this occurs the player 25 may then pull upon the rod 26 to swing the lever 23 upon its pivot 24 in a direction to retract the rod 21, whereupon the hook-like element 20 is tilted to release the ring, and allow the latter to swing back to its normal 30 position for further play. The lever 23 is normally maintained in the position shown in Figure 1 by means of a coiled spring 31.

For the purpose of scoring the points of the game I employ a register including a 35 casing 32 which is mounted upon the upright support above referred to, and which casing has a sight opening through which the numerals on a rotatable dial 33 can be viewed. These numerals are arranged in an 40 annular series about the dial 33, which also has associated therewith a toothed wheel 34. In the normal position of the dial 30 the zero 35 is arranged directly behind the sight opening of the casing 32, while the numerals on this dial run from 1 to 5, as 45 shown in Figure 5. The register is operated manually by the rod 26 above referred to, inasmuch as the toothed wheel 34 is turned one degree each and every time the rod 26 50 is operated to release the ring 18 from the hook-like element 20, as described. In other words, a bell crank lever is pivoted at 36 within the casing 32, one branch 37 of said lever projecting from the casing and connected by a cable 38 to an arm or extension 39 which projects from a lever 23, as shown in Figure 1. The other branch 40 of this bell crank lever pivotally supports a pawl 41 arranged to engage the teeth 42 of the 55 wheel 34 singly, and thus turn the wheel one degree with each operation of the bell crank lever just referred to. Consequently, after the ring 18 has been thrown over the 60 stationary member 19 and the hook-like element 20, the latch element 28 is released

to permit movement of the lever 23 to actuate the rod 21 and thus effect a release of the ring 18. During this operation of the lever 23, a pull is exerted upon the cable 38, thereby operating the bell crank lever in a manner to turn the wheel 34 and the dial 33 one step or degree, bringing the next numeral on the dial before the sight opening in the casing 32. After the ring has been separated from the stationary member 19, and the point of the game recorded, the rod 26 is released, whereupon the spring 31 functions to return the parts to their normal position, as shown in Figure 1. Each player is allowed to throw the ring 18 in the direction of the stationary member 19 five times, and the player who scores the highest number of points in this given number of trials is the winner of the game. The invention also comprehends the provision of means for rendering the apparatus inoperative after eachs participant makes his fifth or final try to ring the stationary member 19, and this is accomplished by swinging the movable section 14 of the beam, from which the ring 18 is suspended, upwardly at an angle to the section 13, thus arranging the ring 18 with relation to the stationary member 19 to make it impossible to ring the latter under any conditions. This section 14 of the beam supports an upright 42 which is connected with one end of a coiled spring 43, the other end of which is connected to a lug 44 rising from the stationary section 13 of the beam. Arranged beneath this spring and pivoted on the stationary section 13 is a lever 45 which is designed to engage the upright 42 and hold it immovable against the tension of the spring 43. Journaled on the stationary section 13 is a toothed wheel 46, the wheel being provided with five teeth, one of which indicated at 47 is longer than the other teeth. Projecting from the arm 16 is a rod 48 adapted to engage the adjacent tooth of the wheel 46 upon each operation of the arm, when the ring 18 is swung in the direction of the stationary member 19. When the ring swings away from the stationary member 19 the wheel 46 is turned one degree, and consequently when the player has swung the ring 18 for the fifth and final time in the direction of the stationary member 19, the large tooth 47 is brought into a position to engage the lever 45 and separate it from the upright 42, thereby releasing the latter to allow the spring 43 to function and throw the upright 42 and movable section 14 of the beam to the position illustrated in the drawings. The parts remain in this position until the ring is pulled downwardly to lower the section 14 into its normal position, whereupon the upright 42 is again engaged by the lever 45.

When the section 14 is lowered in the manner just described, the register is reset, that

is to say, the toothed wheel 34 is released from the pawl 41 to allow the spring 49 to turn the register back to zero. This is accomplished by means of a disk 50 journaled on the upper end of the upright supporting structure and which wheel is formed with a notch 51, and connected by means of a cable 52 with the pivoted pawl 41. A rod 53 is supported by the upright 42 forming part of the movable section 14 of the beam, and projects in the direction of the disk 50, sliding through a suitable guide 54 and terminating to provide a loop 55. When the upright 42 is tilted by the spring 43, the rod 53 is moved in the direction of the disk 50 until the loop 55 passes over the disk and is received by the notch 51. Therefore, when the ring 18 is lowered from its inactive to its active position, a pull is exerted upon the rod 53, and inasmuch as the loop 55 of this rod is arranged in the notch 51 of the disk 50, the latter is partially rotated, exerting a pull upon the cable 52. This cable under the circumstances lifts the pawl 41 away from the toothed wheel to allow the spring 49 to reset the register.

While it is believed that from the foregoing description the nature and advantages of the invention will be readily apparent, I desire to have it understood that I do not limit myself to what is herein shown and described, and that such changes may be made when desired as fall within the scope of what is claimed.

Having thus described the invention, what is claimed as new, is:—

1. A game apparatus comprising a stationary member, a ring supported for swinging movement and adapted to be swung over the stationary member, a register, means for releasing the ring from the member, and means for simultaneously operating said register to score the points of the game.

2. A game apparatus comprising a supporting structure, a stationary member projecting therefrom, a ring suspended from said structure and adapted to be swung in the direction of the stationary member to engage the latter, means for releasing the ring from the stationary member, a register, means for operating the register simultaneously with the release of said ring to score the points of the game, and means for resetting said register.

3. A game apparatus comprising a supporting structure, a stationary member projecting therefrom, a ring suspended from said structure and adapted to be swung in the direction of said member to engage the latter, means including a single control element for releasing the ring from said member, a register, means for operating the register from said control element incident to the release of said ring, and means for resetting said register.

4. A game apparatus comprising a supporting structure, a stationary member projecting therefrom, a ring suspended from said structure and adapted to be swung in the direction of said member to surround the latter, means including a single control element for releasing the ring from said member, a register, means actuated from said control element for operating the register incident to the release of the ring from said stationary member, means for normally holding said control element immovable and adapted to be released by the ring when supported on said stationary member, and means for resetting the register.

5. A game apparatus comprising a supporting structure, a stationary member projecting therefrom, a ring suspended from said structure and adapted to be swung in the direction of said member to encircle the latter, a hook-like element pivoted on said member and normally arranged to hold the ring thereon, means including a manually operable rod for tilting said hook-like member to effect a release of the ring from said stationary member, a register, means actuated by said manually operable rod for operating said register incident to the release of the ring from said stationary member, means for normally holding said hook-like element and operating rod immovable, and adapted to be actuated by the weight of the ring to effect a release of said parts, means for returning the operating rod and its associated parts to normal position after each operation, and means for resetting the register.

6. A game apparatus comprising a supporting structure, a stationary member projecting therefrom, a ring suspended from said structure and adapted to be swung in the direction of said member to encircle the latter, a hook-like element pivoted on said stationary member and adapted to be tilted to effect a release of the ring from said member, means including a reciprocating rod connected with said hook-like element for operating the latter, a pivoted latch designed to engage said rod for normally holding the latter and said hook immovable, and adapted to be operated by the weight of said ring to effect a release of said rod, a register, means for operating said register simultaneously with the release of the ring from said stationary member, and means for resetting the register.

7. A game apparatus comprising a supporting structure including a beam, a stationary member projecting from the supporting structure, said beam including a hinged section, a ring suspended from said section and adapted to be thrown in the direction of the stationary member to encircle the latter, means for releasing the ring from said member and including a manually op-

erable control element, a register, means for operating said register from the control element incident to the release of the ring from said stationary member, ring actuated means for normally holding said control element immovable, means for automatically tilting the pivoted section of said beam at predetermined intervals to arrange the ring in an in-

active position, said ring being adapted to be manually lowered to its active position 10 for further use, and means operated incident to the lowering of said ring for resetting said register.

In testimony whereof I affix my signature.

FRANK J. LASKOWSKI.
